CARRYING CASE FOR TOY CARS

Leonard R. Moquin, Los Angeles, Calif., assignor to Mattel, Inc., Hawthorne, Calif., a corporation of Delaware

Continuation-in-part of design application Ser. No. 11,084, Mar. 21, 1968. This application Dec. 11, 1968, Ser. No. 14,896

Term of patent 14 years

Int. Cl. D3—99

U.S. Cl. D87—1

FIG. 1 is a perspective view of a carrying case for toy cars showing my new design;

FIG. 2 is a front elevational view thereof;

FIG. 3 is a side elevational view of one side thereof.

The rear face of the case is flat and plain.

This is a continuation-in-part of design application Ser. No. D. 11,084, filed Mar. 21, 1968, and now abandoned.

I claim:

The ornamental design for a carrying case for toy cars, as shown and described.
